UNITED STATES PATENT OFFICE.

PASKLE WARREN, OF PEORIA, ILLINOIS.

LOCOMOTIVE STAKE.

Application filed March 10, 1922. Serial No. 542,568.

To all whom it may concern:

Be it known that I, PASKLE WARREN, a citizen of the United States, and a resident of Peoria, in the county of Peoria and State 5 of Illinois, have invented certain new and useful Improvements in Locomotive Stakes, of which the following is a full, clear, and exact description, reference being had to the accompanying drawing, forming part of the 10 specification.

My invention relates primarily to the means by which cars are moved by a locomotive, when the locomotive is on one track and the car on the other, these means being 15 ordinarily called stakes.

One object of my invention is the provision of a stake which is attached to the locomotive and is provided with means whereby the operator does not have to hold the stake in 20 a socket on the locomotive, and the provision of further means to prevent either end of the stake from striking the ground with the resulting liability of an accident.

Another object of my invention is the provision of a stake which may be used to move a car in either direction from a given 25 end of the locomotive.

Other objects of my invention will appear and be described in the specification.

The novelty of my invention will be hereinafter more fully set forth and specifically 30 pointed out in the claims.

In the accompanying drawings:

Fig. 1, is a plan view of the pilot, and 35 pilot beam of an ordinary locomotive showing a pair of my stakes applied thereto.

Fig. 2, is an enlarged sectional view of the pilot beam of Fig. 1, taken on the dotted line 2—2.

Fig. 3, is a broken detail of the rear end 40 of a tender, showing one of my stakes attached thereto.

Fig. 4, is a plan view of Fig. 3.

Fig. 5, is an enlarged detail of the connecting block of stake shown in Figs. 3 45 and 4.

The same numerals of reference are used to indicate identical parts in all the figures.

Referring more particularly to Figs. 1 50 and 2, the pilot beam 1, is provided with socket at each end by means of which a connecting block 2, is attached to the pilot beam, this block being provided with a trunnion or stem 3, which passes through 55 the beam 1 and upper and lower bearing

plates 4 and 5, which are secured to the beam by bolts 6.

A pin 7 passes through the upper portion of the connecting block 2, and the forked end 8, of the stake 9, thereby pivotally 60 mounting the stake on the connecting block 2. The stake is prevented from being lowered beyond a predetermined point by a lug 10, which extends from the connecting block 2 and upon which the forked end 8 65 of the stake rests, though the free end of the stake may be raised if desired.

A saddle 11 is mounted adjacent the center of the pilot beam and the two stakes rest in the depressions of the saddle when 70 not in operation.

When staking a car while the locomotive is moving forward, the stake is placed in the position of the dotted lines 12, while if the locomotive is moving backward the stake 75 is placed in the position of the dotted lines 13.

If the car being handled is on the opposite side of the locomotive, the stake on the other end of the pilot beam is used and 80 adjusted as required.

Referring now to Figs. 3, 4, and 5, the forked end 8, of the stake 9, is attached by means of the pin 7 to the connecting block 14 which, as shown more clearly in Fig. 5, 85 is provided with a vertical opening for the reception of the pin 15 of Figs. 3 and 4, and a horizontal opening for the reception of the pin 7, and the lug 10, similar in construction and arrangement and for the same purpose as the lug 10 previously described.

The pin 15, Figs. 3 and 4, passes through plates 16, which are secured to the upper and lower faces of the frame 17 of the tender. A latch 18 is provided so that when the stake is not in use, it may be placed within the channel of frame 17, and held there against accidental movement. The tender carries a similar stake on the other side of its rear end, and these stakes, like those described as being mounted on the pilot, may be moved to the dotted positions 12 and 13, to move cars in either direction as previously described.

The stake is preferably made of tubing and is capped at its free end by any suitable cap 19, which may be formed to fit the sockets ordinarily carried by the ends of cars, or this cap may be forked to engage the corner of a car as desired.

It will be noted from the above that a locomotive equipped with my stakes may be used to move a car in either direction from either end of the locomotive and that while the stake is being used, there is no likelihood of the trainman being injured, and there is no possibility of the stake dropping to the ground or on the track and derailing either the car or locomotive as frequently happens with the stakes now in use. Further a stake constructed as above described does not have to be carried by the trainman and held between the locomotive and the car, and after use, if the stake on the pilot has been used, it is replaced in the saddle 11, and if the stake on the rear of the tender has been used, it is folded into the position shown in Figs. 3 and 4, and locked in place by the handle 18, thus saving the time required

to carry the ordinary stake to the hooks provided for it, and placing it thereon.

Having thus fully described my invention, I claim

1. In a stake the combination of a stake member, a connecting block provided with a movement limit and to which the stake member is pivotally connected on a horizontal axis, and a pivotal mounting for the connecting block on a vertical axis.

2. In a stake the combination of a stake member, a connecting block carrying a movement limit and through which the stake member is pivotally connected on a horizontal axis, a pivotal mounting for the connecting block on a vertical axis, and means for holding the stake in a predetermined position against accidental misplacement.

PASKLE WARREN.
